UNITED STATES PATENT OFFICE.

CHARLES PFAU, OF CINCINNATI, OHIO.

DESIGN FOR A TANK.

46,065.

Specification for Design.

Patented July 7, 1914.

Application filed April 11, 1914. Serial No. 831,120 $\frac{1}{2}$. Term of patent 14 years.

To all whom it may concern:

Be it known that I, CHARLES PFAU, a citizen of the United States, residing at Cincinnati, in the county of Hamilton and State of Ohio, have invented a new, original, and ornamental Design for Tanks, of which the following is a specification, reference being had to the accompanying drawing, forming part thereof.

The figure is a perspective view of my new design.

I claim:

The ornamental design for a tank, substantially as shown.

CHARLES PFAU.

Witnesses:

JAMES N. RAMSEY,
IRENE PARKER.
